CONTAINER FOR ACOUSTICAL TILE OR
THE LIKE

Harold W. Layne, Sr., Beech Grove, Ind., assignor to In-
land Container Corporation, Indianapolis, Ind., a cor-
poration of Indiana

Filed June 14, 1966, Ser. No. 557,421
2 Claims. (Cl. 229—14)

ABSTRACT OF THE DISCLOSURE

A container having foreshortened and flaps with a reinforcing panel at each end of the container, the reinforcing panel carrying cushioning pads along two opposite margins, the inner edges of the pads aligning with the edges of the adjacent end flaps to form hand grip ledges at each end of the container.

This invention relates generally to reinforced containers and in particular to a shipping and transport container for somewhat fragile articles such as acoustical building tile.

The container or carton of the present invention is primarily adapted to accommodate building tile or acoustical building tile, a rather fragile and easily damaged product. Fracture of the tiles can easily occur at their corners and edges, particularly, and the container of the present invention protects these areas. Tiles of the type referred to, after shipment to the construction or installation site, are usually carried to the various floors of the building under construction by unskilled workmen. Any careless handling or dropping of the tile carton can, of course, damage the contents. To prevent or minimize such damage the container of the present invention integrates or combines the reinforcing members with the outer shell or container proper so as to provide convenient hand grips to be used in manual lifting and carrying of the filled cartons. The carton of the present invention further organizes the parts providing the features mentioned above so that the carton can be readily opened to expose the tile for easy removal from the carton.

It is the primary object of the present invention to provide a container for acoustical tile or the like in which container reinforcement components and the portion forming the outer shell of the container are combined to provide integral hand grip areas on the container, the container being capable of being opened to expose a large area of its contents to facilitate emptying of the container.

This and other objects will become apparent as the description proceeds with reference to the accompanying drawings in which:

FIG. 1 is an exploded, perspective view of a container embodying the present invention.

FIG. 2 is a perspective view of the complete, closed container of FIG. 1.

FIG. 3 is a fragmentary, top plan view of the blank from which the container of FIG. 1 is formed.

FIG. 4 is a perspective view of the container of FIG. 1 but showing the container opened to expose its contents.

FIG. 5 is an exploded, perspective view of a modified form of the invention.

FIG. 6 is a perspective view of the container of FIG. 5 when closed.

FIG. 7 is a perspective view of the container of FIG. 5 after being opened to expose its contents.

FIG. 8 is an exploded, perspective view of a further modified form of the invention.

FIG. 9 is a perspective view of the container of FIG. 8 in closed condition.

2

FIG. 10 is a perspective view of a further modified form of the present invention.

FIG. 11 is a perspective view of a reinforcing panel utilized in the container of FIG. 10.

FIG. 12 is a perspective view of a further modified form of the present invention.

FIG. 13 is a perspective view of a still further modified form of the present invention.

Referring initially to FIGS. 1, 2, 3 and 4, a container embodying the present invention is shown as comprising a top panel 10, a bottom panel 11 and side panels 12 and 13. The top panel 10 is composed of two edge abutting top panel sections 10a and 11b of equal width and each extending from the upper margin of the adjacent side panel. The top panel sections 10a and 10b are releasably joined at their free margins by removable adhesive tape identified at 14.

The ends of the container are formed by end flaps 16 and 17 which extend from the side panels 12 and 13 respectively and by end flaps 18, 19 and 21 which extend from top panel sections 10a and 10b and from bottom panel 11 respectively. The end flaps 16 and 17 are notched and perforated or scored, or otherwise weakened along a transverse line identified at 16a and 17a respectively. In the drawings only one end of the container is shown in detail, however, it will be understood that the end not shown has end flaps which duplicate those illustrated. Longitudinal score lines 12a and 13a bisect the side panels 12 and 13 respectively and the score lines extend between the inner terminations of the tear lines 16a and 17a of the adjacent end flaps.

As may best be seen in FIG. 2 the free margins of corresponding end flaps oppose each other but terminate substantially short of abutting engagement and thereby leave a generally rectangular opening 23 in each of the container ends. As indicated in FIGS. 2 and 3 the corners of the top panel section end flaps 18 and 19 may be provided with an ink spot (preventing adherence of the tape 14 at the spotted areas) indicated at 24 to facilitate starting of the peeling of the tape when the container is to be opened.

Referring again primarily, to FIG. 1, the product or contents, which may take the form of rectangularly shaped acoustic tile indicated generally at 26, may have enclosing it a liner or rectangularly shaped tube 27 which is wrapped around the exterior of the product. Each end of the container is provided with a reinforcing panel 28 which is sized to closely fit within the container ends and to underlie the end flaps, as will be evident from FIG. 2. The panels 28 are provided with cushioning pads 28a and 28b which extend along the upper and lower marginal areas of the panels 28, respectively. The cushioning pads 28a and 28b have a width or depth which is substantially equal to the length of the adjacent end flaps 18-19 and 21 so that the inner marginal, longitudinal edge of the cushioning pads is generally aligned with the free margins of the adjacent end flaps 18-19 and 21. As shown in FIG. 1, the cushioning pads are on the face of the reinforcing panels adjacent the contents of the container, although in modified forms of the invention to be described subsequently these cushioning pads may be located on the opposite face of the reinforcing panels. The reinforcing panels are further provided with a generally rectangular aperture 31 which, in general, registers with the aperture 28 in the ends of the container formed by the foreshortening of the end flaps. The cushions 28a and 28b may be formed by separate elements or can be, as shown in FIG. 1, formed by die cut portions of the panel 28 itself, the panel being formed of double wall corrugated board.

When the container is filled and closed, as shown in FIG. 2, it will be evident that the upper margin of the

aperture 31 in the reinforcing panels and the adjacent margins of the cushions 28a and the end flap sections 18 and 19 form a hand grip ledge indicated at 32 in FIG. 2 by means of which the container may be conveniently lifted and manually transported. The reinforcing panels 28 additionally provide rigidity and shock absorbing cushioning for the contents of the container. As indicated in FIG. 4, when the container is to be emptied, by removing the tape 14 and folding the side panels 12 and 13 outwardly upon themselves along the score lines 12a and 13a respectively, the contents of the container may be exposed for removal. As will be evident from FIG. 4, the folding back of the side panels must, of course, be preceded by the tearing of the end flaps 16 and 17 along the lines 16a and 17a.

Referring now to FIGS. 5, 6 and 7, a modified form of the structure of FIGS. 1-4 will be described. In FIGS. 5, 6 and 7 parts which are identical to those of FIGS. 1-4 are given the same reference numerals. The structure of FIGS. 5, 6 and 7 differs from that previously described in that the reinforcing panels 41 at the ends of the container have their cushioning pads 41a and 41b facing away from the container contents. This arrangement has the advantage that no aperture (comparable to aperture 31 of FIG. 1) need be formed in the reinforcing panels 41 to permit the thickness of the cushioning pads 41a to be utilized in forming the hand grip ledge. As will be evident from FIG. 7 the container of FIGS. 5 and 6 may be opened to expose the container contents for removal in the same fashion as described with regard to FIG. 4.

A further modified form of the container of the present invention is illustrated in FIGS. 8 and 9 and in referring to these figures parts which are identical to those identified in FIGS. 1-4 will be given the same reference numerals. The structure of FIG. 8 differs from that of FIG. 1 and FIG. 5 primarily in that the reinforcing panels at each end of the container have their cushioning pads oriented so as to be parallel to the side panels, rather than the top panels as is the case with the structure of FIGS. 1 and 5. As will be evident from FIGS. 8 and 9, the reinforcing end panels 46 are provided with cushioning pads 46a and 46b which, as shown, face outwardly from the container contents. It will be noted that the pads 46a and 46b are aligned parallel with the side panels 12 and 13 of the container. After the container has been loaded and sealed closed by the removable tape 14, it is turned 90° so as to rest upon one of the side panels and lifting is accomplished by utilizing the hand grip ledge 47 (FIG. 9) formed by the thickness of the cushioning pad 46b and the thickness of the side panel end flap 17.

The structure shown in FIGS. 10 and 11 represents a further modified form of the present invention and in FIG. 10, parts which are identical to those of FIG. 1 are given the same reference numerals as there utilized. In FIG. 10, the side panel end flaps 48 and 49 (which are the counterparts of side panel end flaps 16 and 17 of FIG. 1) are longer and extend into near abutting relationship except for cutaway portions 48a and 49a which define a hand grip aperture. The end reinforcing panels 51, utilized with the container of FIG. 10 are similar to the panels 41 of FIG. 5 but differ in that the cushioning pads 51a and 51b are formed by spaced folds of the corrugated board from which the panel 51 is formed, rather than being formed by face-to-face layers of corrugated board as is the case with the cushions 41a and 41b of FIG. 5. The thickness of the fold forming the cushion 51a, accessible through the opening formed by the cutaway portions 48a and 49a, together with the thickness of the end flaps 18 and 19 define the width of the hand grip ledge identified at 52 in FIG. 10.

FIGS. 12 and 13 illustrate modified forms of the container. In FIG. 12, the container 60 does not utilize reinforcing end panels but provides the end cushions by spaced folding of extending ends of the top and bottom panel end flaps 62, 63 and 64 respectively. In this struc-

ture, the side panel end flaps 66 and 67 are folded over the cushions formed by the end flaps 62, 63 and 64 and the space between the free margins of the end flaps 66 and 67 permits insertion of the fingers of the manipulator of the container under the cushion to grasp the hand grip ledge.

In FIG. 13 the container 71 forms its end cushions by spaced folding of extensions of the side panel end flaps 72 and 73. When the container is to be lifted, it is rotated through 90° so as to rest upon one of its side panels and the hand grip ledge is defined by the underside of the cushion, such ledge being identified at 74 in FIG. 13.

From the foregoing it will be evident that the container of the present invention provides the corner reinforcement necessary for safe transportation of articles such as that referred to and the arrangement of the reinforcing structure (specifically the reinforcing end panels) is such as to provide readily accessible hand grip apertures for manual transportation of the containers at, for example, the job site. As here described, the container, including all its components, are formed of corrugated board, however, it will be recognized that other materials might be utilized, particularly for the cushioning pads carried by the reinforcing end panels.

While the invention has been disclosed and described in some detail in the drawings and foregoing description, they are to be considered as illustrative and not restrictive in character, as other modifications may readily suggest themselves to persons skilled in this art and within the broad scope of the invention, reference being made to the appended claims.

The invention claimed is:

1. A container for semi-fragile articles such as acoustical tile or the like comprising: top, bottom and side panels, said top panel being formed by two edge abutting top panel sections of equal width and each extending from the upper margin of one of the side panels and normal thereto, said top panel sections being releasably joined at their free margins when the container is closed, end flaps extending from said side panels, said bottom panel and from both of said top panel sections and folded to overlie each other to form the container ends, the free margins of corresponding end flaps opposing each other but terminating substantially short of abutting engagement thereby leaving a generally rectangular aperture in the container ends, and a reinforcing panel at each end of the container sized to closely fit within the container ends and to underlie said end flaps, said reinforcing panel having cushioning pads extending along two of its opposed marginal areas, said cushioning pads having a width substantially equal to the length of the adjacent end flaps, said reinforcing panels having a central aperture with margins generally aligned with the inner margins of said reinforcing cushions, said panel aperture registering with said generally rectangular aperture in the container ends whereby the thickness of said reinforcing cushions, the thickness of said reinforcing panel and the thickness of the adjacent end flaps thereby forming a hand grip ledge at each end of the container.

2. A container for semi-fragile articles such as acoustical tile or the like comprising: top, bottom and side panels, said top panel being formed by two edge abutting top panel sections of equal width and each extending from the upper margin of one of the side panels normal thereto, said top panel sections being releasably joined at their free margins when the container is closed, end flaps extending from said side panels, said bottom panel and from both of said top panel sections and folded to overlie each other to form the container ends, the opposed end margins of said flaps being formed to provide an aperture in the container ends, and a reinforcing panel at each end of the container sized to closely fit within the container ends and to underlie said end flaps, said reinforcing panel having cushioning pads extending along two of its opposed marginal areas, said cushioning pads

having a width substantially equal to the length of the adjacent end flaps, the thickness of said reinforcing cushions and the adjacent end flaps thereby forming a hand grip ledge at each end of the container.
